UNITED STATES PATENT OFFICE.

CHARLES HARRY PEET, OF BINGHAMTON, NEW YORK.

DESIGN FOR A TRAY.

SPECIFICATION forming part of Design No. 33,729, dated December 18, 1900.

Application filed November 21, 1900. Serial No. 37,299. Term of patent 3½ years.

To all whom it may concern:

Be it known that I, CHARLES HARRY PEET, a citizen of the United States of America, residing at Binghamton, in the county of Broome and State of New York, have invented and produced a new and original Design for Trays; and I do declare the following to be a full, clear, and exact description of the same, reference being had to the accompanying drawings, forming a part thereof.

Figure 1 is a front view a tray, showing my new design. Fig. 2 is a side view, partially broken away.

As shown in the drawings, the leading or material feature of my design consists of a circular base 1, provided with a flaring outwardly-projecting flange 2, forming the body of the tray. The base has impressed in its face the representation of a buffalo, and below the same and near the flange 2 is represented a scroll 3.

Projecting from the flange 2 is a handle 4, formed in outline of ogee curves meeting at their outer ends and gradually merging into the flange 2 at their inner ends. Surrounding the outline of the handle is the representation of a scroll 5, and at its inner end said scroll merges into and forms part of a relief or scroll 6.

Having thus described my invention, what I claim as new, and desire to secure by Letters Patent, is—

The design for a tray, as herein shown and described.

In testimony whereof I have signed my name to this specification in the presence of two subscribing witnesses.

CHARLES HARRY PEET.
